United States Patent Office

Des. 184,908
Patented Apr. 21, 1959

184,908

SCARF

George Bliss, Jr., Cleveland, Ohio

Application November 7, 1957, Serial No. 48,372

Term of patent 3½ years

(Cl. D3—16)

Fig. 1 is a top perspective view of a scarf showing my new design;

Fig. 2 is a sectional view taken on the line 2—2 of Fig. 1; and

Fig. 3 is a bottom plan view of the same.

I claim:

The ornamental design for a scarf, substantially as shown.
